SWEATER OR SIMILAR ARTICLE

Raymond E. Olson, Minneapolis, Minn.

Application September 2, 1950, Serial No. 12,049

Term of patent 3½ years

(Cl. D3—4)

To all whom it may concern:

Be it known that I, Raymond E. Olson, a citizen of the United States, residing at 2825 East Lake Street, Minneapolis, in the county of Hennepin and State of Minnesota, have invented a new, original, and ornamental Design for a Sweater or Similar Article, of which the following is a specification, reference being had to the accompanying drawing, forming part thereof.

Figure 1 is a front view of the sweater or similar article showing my new design.

Figure 2 is a side view of the sleeve of the sweater or similar article showing its novel design.

The back of the sweater or similar article is like the front portion shown except it does not show the V-design at the upper part nor does the back of the sweater or similar article have the opening and fastening means in the lower portion.

The upper portion and sleeves of the sweater

or similar article are of knitted fabric and the lower portion of the sweater or similar article is made of woven cloth.

I claim:

The ornamental design for a sweater or similar article, substantially as shown and described.

RAYMOND E. OLSON.
